UNITED STATES PATENT OFFICE.

WILLIAM U. COLTHAR, OF SPRINGFIELD, OHIO, ASSIGNOR TO WILLIAM J. JOHNSON, OF YELLOWSPRINGS, OHIO.

SPRING-MOTOR.

SPECIFICATION forming part of Letters Patent No. 744,295, dated November 17, 1903.

Application filed April 24, 1903. Serial No. 154,153. (No model.)

To all whom it may concern:

Be it known that I, WILLIAM U. COLTHAR, a citizen of the United States, residing at Springfield, in the county of Clark and State of Ohio, have invented certain new and useful Improvements in Spring-Motors, of which the following is a specification, reference being had therein to the accompanying drawings.

This invention relates to spring-motors, and has for its object to provide a simple, compact, and efficient motor, which may readily be applied to a sewing-machine, which may be readily controlled as to stopping, starting, and speed by the usual treadle with which such machines are provided and in which the motions given to the treadle in controlling the machine will serve to rewind or aid in rewinding the spring.

To these ends my invention consists in certain novel features, which I will now proceed to describe, and will then particularly point out in the claims.

In the accompanying drawings, Figure 1 is a front elevation showing my improved motor applied to a sewing-machine. Fig. 2 is an end elevation of the same. Fig. 3 is an enlarged detail view, in vertical section, along the main axle. Fig. 4 is a detail sectional view taken on the line $x-x$ of Fig. 3 and looking in the direction of the arrows. Fig. 5 is a similar view taken on the line $y-y$ of Fig. 3 and looking in the direction of the arrows. Fig. 6 is a detail view, on an enlarged scale, of the brake mechanism, taken on the line $z-z$ of Fig. 1 and looking in the direction of the arrows. Fig. 7 is a detail plan section taken on the line $v-v$ of Fig. 1 and looking in the direction of the arrows. Fig. 8 is a detail sectional view through one of the ratchets taken on the line $w-w$ of Fig. 3 and looking in the direction of the arrows; and Fig. 9 is a detail view, partly in longitudinal section, of the extension-lever for operating the main winding-ratchet.

In the said drawings, 1 indicates the sewing-machine proper, having on its main shaft the usual pulley 2, by means of which it is driven. This machine is mounted on the usual table 3, supported at its ends by the leg-frames 4 and braced by the central bracket

5. These parts may, of course, be of any approved construction.

Referring more particularly to the motor, it comprises an axle 6, supported in suitable bearings in the leg-frames and bracket. In the present instance I have shown it mounted in the same position as the usual fly-wheel shaft of the driving mechanism of the machine. Said axle has one of its bearings at 7 in the bracket 5 and is further supported by frame-plates 8 and 9, connected together by bolts 10 and supported from the supporting-legs and brackets of the table in any suitable manner.

10 indicates a coiled spring, secured at one end to the axle 6, as indicated at 11, its other end being secured to a casing 12, as indicated at 13, said casing being mounted on the axle 6, so as to be free to rotate thereon. The spring-casing 12 carries an internal gear 14 and is provided with a plate 15, which incloses the spring on the open side where the internal gear is located and holds said spring in position within the casing. The internal gear 14 meshes with a pinion 16, mounted on a stud-shaft 17, projecting from the frame-plate 8, and said pinion 16 is connected with a gear 18, also mounted on said shaft 17, so that the pinion and gear rotate together. The frame-plate 8 is further provided with a second stud-shaft 19, on which are mounted, so as to rotate in unison, a pinion 20 and gear-wheel 21. The pinion 20 meshes with the gear-wheel 18, while the gear-wheel 21 meshes with a pinion 22, secured on the hub 23 of a combined fly-wheel and driving-pulley 24, which is mounted loosely on the axle 6 between the frame-plates 8 and 9. It will thus be seen that a comparatively slow rotation of the spring-casing 12 and its gear 14 will impart a relatively rapid movement of rotation to the driving-wheel 24, and this motion is transmitted to the driving-pulley 2 of the sewing-machine proper by means of a suitable belt 25.

In order to control and regulate the running of the machine so as to readily stop it or start it and regulate its speed while running, I employ a brake mechanism utilizing the usual treadle 26 and treadle-shaft 27 of the sewing-machine. To this end there is

95
90
100

secured on the treadle-shaft 27 an arm 28, having an inclined or cam portion 29, in the path of which lies a rod 30, pivoted at its lower end at 31 to any suitable support—as, 5 for instance, the lower part of the bracket 5. The upper end of this rod carries a pin 32, which passes through a guide-opening 33 in the frame-plate 8, the inner end of said pin lying immediately adjacent to the rim of the 10 wheel 24, against which it is pressed when the rod 30 is engaged by the cam 29. This pin thus acts as a friction-brake against the wheel and regulates its speed or entirely arrests its motion, as desired, such regulation 15 or stopping being effected by a rocking movement of the treadle 26. The brake-pin 32 is preferably provided with a covering 34, of rubber or the like, to afford a more efficient and readily replaceable friction-surface. The 20 pin is disengaged when the cam is moved out of contact with the rod 30 by reason of the fact that its pivot is located to one side of its center of gravity, as shown in Fig. 1. A resilient arm might, however, be substituted 25 for the pivoted arm or rod shown.

In the ordinary use of a sewing-machine it is being frequently stopped and started or its speed changed, according to the character of the work, and I propose to utilize the movements 30 of the treadle by which this regulation is effected in order to rewind or aid in rewinding the spring of the motor. To this end there is secured on the axle 6 a ratchet-wheel 35, and on each side of said ratchet-wheel 35 there is mounted loosely on the axle 6 a vibrating arm, (indicated at 36 and 37.) These arms are connected by links or pivoted rods 38 and 39, respectively, with the treadle 26 at a point 26^a eccentric to its pivotal axis. 40 It will thus be seen that when the side of the treadle carrying the pivot 26^a is depressed both of the arms 36 and 37 will be similarly depressed and when said portion of the treadle is raised both of the arms will be similarly raised. This movement of the arms toward and from each other is illustrated in full and dotted lines in Fig. 4. The arm 36 has mounted in it a plurality of sliding pawls or dogs 40, preferably four in number and arranged 45 at a distance apart slightly greater than the distance between the teeth of the ratchet-wheel 35. These pawls are pressed inward into engagement with the ratchet-wheel 35 by means of springs 41, and their location and arrangement are such that one of them is always in engagement with the radial face of one of the ratchet-teeth, so that whenever the arm 36 moves downward the ratchet-wheel and axle 6 will be rotated in such a 50 direction as to wind the spring 10, there being practically no lost motion before the engagement of one of the pawls with the ratchet-wheel. The arm 37 is provided with similar pawls or dogs 42, similarly spaced apart and forced into engagement with the ratchet-wheel by springs 43, and their arrangement is such that any upward movement of the arm

37 will rotate the ratchet-wheel 35 and axle 6 in the same direction and further wind the spring 10. Thus every movement of the 70 treadle, no matter how slight or in what direction, will partially rewind the spring of the motor, and in practice I have found that little or no other winding of said spring is required. It will be understood, of course, 75 that the ratchet-wheel 35 and the pawl-carrying arms engaging therewith prevent free rotation of the axle 6 and cause the spring to exert its force upon the driving-wheel 24. The treadle has at no time any part in the 80 actual driving of the sewing-machine, as this driving is accomplished entirely by the spring-motor. The treadle does, however, have two functions, operating at one and the same time to control the speed of the sewing-machine 85 and rewind the spring of the motor. The device as a whole is especially adapted for domestic use where power is not available, as in a factory. In such domestic use the class of sewing usually done is such that the seams 90 are frequently very short, involving a frequent stopping and starting of the machine. At the same time the character of the goods, the size and shape of the articles operated on, and the frequent deviations of the seams 95 from a straight line all tend to require frequent slowing down of the sewing-machine, as well as frequent stoppages, and of course equally frequent increases in speed and startings. It is found in practice that in this class 100 of work the constant movements of the treadle in stopping and starting, slowing down, and increasing speed are sufficient to keep the spring of the motor wound up to such an extent that recourse to the main winding device hereinafter referred to is seldom required.

In order to make provision for winding the spring 10 at any time when the rewinding just described is not sufficient, I provide upon 105 the outer end of the axle 6 a ratchet-wheel 44, removably secured thereon by a pin 45. This ratchet-wheel is embraced by an oscillating band-wheel 46, mounted on the hub 47 of said ratchet-wheel and preferably made 110 in two parts, as shown. One of these parts (indicated at 48) has an annular projection 49, in which are mounted to slide radially pawls or dogs 50, adapted to engage the ratchet-wheel 44, and held in such engagement by a spring 51, passing through apertures 52 in the outer ends of said pawls. The other member of this wheel (indicated at 53) 115 is provided outward from the annular flange 49, but inward from the periphery of the 120 wheel, with an annular flange 54. The two parts are united by screws 55, passing through the body of the part 53 into the annular flange 49. The space 56 between the flanges 49 and 54 accommodates the spring 51 and 125 gives room for the outward movement of the pawls 50. The space 57 lying outward from the flange 54 forms a peripheral groove to receive a band or strap 58, one end of which is 130

secured to the band-wheel 46, while the other end is secured at 59 to a hand-lever 60, pivoted at 60^a to the frame of the machine. This lever is made in two parts, so as to be extensible, and comprises a body portion 61, having an aperture 62, in which fits and slides a rod 63, and provided at one end with a hand-grasp 64 and at the other end with a head or enlargement 65. The bore 62 is enlarged at that end thereof nearest the pivot 60^a, as shown at 66, so as to permit the entry into it of the head 65, so that while the lever 60 is not in use it may lie in the compact form shown in Fig. 2, not projecting materially beyond the frame of the machine. When required for use, however, it may be extended by pulling upon the hand-grasp 64 until the enlargement 65 comes into contact with the shoulder 67, formed at the junction of the bores 62 and 66, whereupon downward pressure on the handle 64 will cause the band-wheel to rotate, carrying the ratchet-wheel 44 along with it, and thus so rotating the axle 6 as to wind the spring 10. The return of the parts is effected by a spring 68, surrounding the hub 47 of the ratchet-wheel and having one end connected to the frame member 4 or some other fixed part, while its other end is connected to the band-wheel. By reason of this construction the spring 10 may be readily and quickly wound, and the lever 60 may be lengthened more or less, so as to increase or diminish the leverage, as desired.

It will be observed that there are two winding mechanisms connected with the motor, one of which, operated by the hand-lever, gives the spring its initial winding and may therefore be termed the "main" winding mechanism, while the other, operated by the treadle, rewinds the spring during the operation of the sewing-machine and may therefore be called the "auxiliary" winding mechanism. These two winding devices, in conjunction with the brake mechanism and the foot-treadle operatively connected with and simultaneously actuating both the brake mechanism and the auxiliary winding device, constitute as a whole an organized mechanism whereby the length of the operative period of the sewing-machine before the motor finally runs down, so as to require rewinding by the main winding device, is extended far beyond to what it would be were the auxiliary winding device and the mechanism for operating it in conjunction with the brake mechanism omitted. It should also be noted that the ratchet mechanism constituting a part of the auxiliary winding mechanism serves also as a detent mechanism to prevent the uncoiling of the spring when wound by the main winding mechanism.

The entire motor constructed in the manner shown may be applied to the supporting frame of sewing-machines already built and does not require a special structure of supporting-frame for its application.

I do not wish to be understood as limiting

myself to the precise details of construction hereinbefore described, and shown in the accompanying drawings, as it is obvious that these details may be modified without departing from the principle of my invention.

Having thus fully described my invention, what I claim as new, and desire to secure by Letters Patent, is—

1. The combination, with a sewing-machine, of a spring-motor therefor, means connecting said motor with the sewing-machine to drive the same, a main winding mechanism, an auxiliary winding mechanism, a brake mechanism, a treadle, means connecting the treadle and brake mechanism whereby the former operates the latter, and means connecting the treadle and auxiliary winding mechanism whereby said auxiliary winding mechanism is actuated by the brake-controlling movements of the treadle, substantially as described.

2. The combination, with a sewing-machine, of a spring-motor therefor, means connecting said motor with the sewing-machine to drive the same, a main winding mechanism, an auxiliary winding mechanism, a brake mechanism, a treadle, means connecting the treadle and brake mechanism whereby the former operates the latter, and means connecting the treadle and auxiliary winding mechanism whereby said auxiliary winding mechanism is actuated by the brake-controlling movements of the treadle, said auxiliary winding mechanism comprising a ratchet-wheel with which one end of the motor-spring is connected, vibrating arms located on opposite sides of the ratchet-wheel and each provided with pawls to engage said ratchet-wheel, and means connecting said vibrating arms with the treadle, whereby said arms are moved simultaneously in opposite directions, substantially as described.

3. In a spring-motor, the combination, with a normally stationary axle provided with a ratchet-wheel, of a coiled spring connected with said axle, a gear-train driven by said spring, a wheel driven by the gear-train, a band-wheel loosely mounted adjacent to the ratchet-wheel and provided with pawls to engage the same, a vibrating lever, a band connecting said lever and the band-wheel, a spring for returning said band-wheel and lever to normal position, and a ratchet device for preventing reverse rotation of the main axle, substantially as described.

4. In a spring-motor, the combination, with a normally stationary main axle, a ratchet-wheel thereon, a coiled spring connected with said axle, and a gear-train driven by said spring, of a band-wheel provided with pawls to engage the ratchet-wheel, a band connected with said wheel at one end, and a vibrating lever connected to the other end of said band-wheel, said vibrating lever being composed of two relatively sliding sections, whereby its length may be extended or decreased, substantially as described.

5. In a spring-motor, an axle having two ratchet-wheels thereon, a coiled spring connected to said axle, a gear-train driven by said spring, a wheel driven by said gear-train, a 5 brake controlling said wheel and train, a treadle controlling said brake, two vibrating arms mounted loosely on the axle and provided with pawls to engage one of the ratchet-wheels, said arms being operatively connected with the treadle, whereby the movements of said treadle in either direction serve to wind the spring, a band-wheel loosely mounted adjacent to the second ratchet-wheel and provided with pawls to engage the same, a vi- 10 trating lever, a band connecting said vibrating lever and band-wheel, and a spring to return said vibrating lever and band-wheel to normal position, substantially as described.

6. The combination, with a sewing-machine proper and its supporting-table, of a spring-motor mounted in the supporting-frame of said table and comprising a normally stationary axle provided with a ratchet-wheel, a coiled spring connected to said axle, a gear- 15 train driven by said spring, a combined driving and fly wheel driven by said gear-train and connected with the sewing-machine proper to drive the same, a movable brake-arm mounted on the supporting-frame of the sewing- 20 machine and normally out of engagement with the driving-wheel, a treadle-shaft, a treadle, a cam mounted on the treadle-shaft of the sewing-machine to operate said brake-arm, vibrating arms loosely mounted on the axle and provided with pawls to engage one of said 25 ratchet-wheels from opposite sides, links pivoted to said arms and to the treadle of the sewing-machine, a loosely-mounted band-wheel adjacent to the second ratchet-wheel and provided with pawls to engage the same, 30 a vibrating extensible hand-lever mounted on the supporting-frame of the sewing-machine, a band connecting said last-mentioned lever and band-wheel, and a spring to return said last-mentioned lever and band-wheel to normal position, substantially as described.

35 and provided with pawls to engage the ratchet-wheel from opposite sides, and links pivoted

to said arms and to the treadle of the sewing-machine, substantially as described.

7. The combination, with a sewing-machine proper and its supporting-table, of a spring- 40 motor mounted in the supporting-frame of said table and comprising a normally stationary axle provided with two ratchet-wheels, a coiled spring connected to said axle, a gear-train driven by said spring, a combined driv- 45 ing and fly wheel driven by said gear-train and connected with the sewing-machine proper to drive the same, a movable brake-arm mounted on the supporting-frame of the sewing-ma- 50 chine and normally out of engagement with the driving-wheel, a treadle-shaft, a treadle, a cam mounted on the treadle-shaft of the sewing-machine to operate said brake-arm, vibrating arms loosely mounted on the axle and provided with pawls to engage one of said 55 ratchet-wheels from opposite sides, links pivoted to said arms and to the treadle of the sewing-machine, a loosely-mounted band-wheel adjacent to the second ratchet-wheel and provided with pawls to engage the same, 60 a vibrating extensible hand-lever mounted on the supporting-frame of the sewing-machine, a band connecting said last-mentioned lever and band-wheel, and a spring to return said last-mentioned lever and band-wheel to nor- 65 mal position, substantially as described.

In testimony whereof I affix my signature in presence of two witnesses.

WILLIAM U. COLTHAR.

Witnesses:

E. O. HAGAN,
IRVINE MILLER.
